UNITED STATES PATENT OFFICE

GUSTAV ULLMANN, OF VIENNA, AUSTRIA, AND WILLY SECK, OF AUGSBURG, GERMANY

PROCESS FOR CARRYING OUT WASHING OPERATIONS WITH HARD WATER

No Drawing. Application filed November 9, 1928, Serial No. 318,305, and in Austria August 5, 1927.

The inventors have described a process for carrying out washing operations with hard water, which consists in rendering the hardening constituents and salts present in the washing water harmless by adding to the water as well as ordinary soap a soap indifferent to the substances which cause hardness in an amount which is less than the quantity stoichiometrically equivalent to the substances which cause hardness. Soaps of this kind are obtained in known manner by sulphonating fats, oils, fatty acids, resins and the like and saponifying the sulphonated products.

The invention consists in employing for washing operations with hard water instead of the special soaps specified, which can be termed oil preparations, less than stoichiometric quantities of organic substances which are considerably more indifferent to lime and other water-hardening substances than the aforementioned oil preparations. These new bodies are derivatives of organic aromatic sulphonlic acids or condensation products of the latter with aliphatic sulphonlic acids, which on the one hand are distinguished by forming water-soluble salts with lime etc., and on the other hand, owing to their high molecular weight possess marked colloidal properties.

These sulphonlic acids like the oil preparations indifferent to lime mentioned above may be employed in amounts which are less than the quantities stoichiometrically equivalent to the substances which cause hardness in order to avoid the separation in soaping operations of lime soaps in the known sticky form and to effect the separation of a finely-divided easily washable precipitate. This observed fact was all the more surprising as aromatic sulphonlic acids of this kind in contradistinction to the oil preparations do not resemble true soaps either in their composition or in their properties.

Examples of aromatic sulphonlic acids of this kind which have the action required for the process are in the first place the recently discovered aromatic or hydro-aromatic sulphonlic acids with alkyl side chains. The employment of products of this kind as wet-

ting agents and soap substitutes is known, not however, their use in soaping operations in less than stoichiometric quantities. Further, all compounds, which are obtained by the treatment of fatty oils with the above mentioned sulphonlic acids, particularly the alkylated aromatic or hydro-aromatic sulphonlic acids, either alone or in the presence of free sulphuric acid, belong to this group of bodies. These products also, which partially owing to their preponderating content of aromatic compounds are no longer to be considered as actual oil preparations, may be employed with equal success for the process according to this invention. Finally, the sulphonlic acids contained in the decalcified sulphite waste liquor by conversion of the sulphurous acid ester fall in the group of the above mentioned compounds.

Example 1.—Utility water having 18 German degrees of hardness (a German degree of hardness corresponding to one part of calcium oxide per 100,000 parts of water) with which textile goods are to be washed, that is soaped and rinsed, is employed. A soap bath is prepared from $2\frac{1}{2}$ grams of soap containing 60% of fatty acid and 0.40 to 0.55 grams of isopropyl or di-isopropyl naphthalene sulphonlic acid per litre.

Example 2.—The same procedure is followed as in Example 1. In place of isopropyl naphthalene sulphonlic acid, a product, which is obtained by the sulphonation of naphthalene or anthracene or phenanthrene in the presence of other secondary or tertiary alcohols which contain more than three carbon atoms, is employed in quantities corresponding to its lime-fixing power. In the same way, the hydrides of these bodies such as, for example, tetrahydronaphthalene-isopropyl-sulphonlic acid may be employed.

Example 3.—Water having 18 German degrees of hardness and 2.5 grams of soap per litre are used as in Example 1 for the soaping operation. There is added 0.65 grams of a product which is obtained by treating castor oil with one of the sulphonlic acids mentioned in Example 1. The quantity 0.65 grams refers to a preparation which contains 30% of ricinoleic acid.

Example 4.—Water having 18 German degrees of hardness and 2.5 grams of soap per litre are used as in Example 1 for the soaping operation. In place of the preparation mentioned in Example 3, 0.65 grams of a 30% product which results from the treatment of castor oil with a mixture of concentrated sulphuric acid and one of the above mentioned aromatic sulphonic acids is employed.

10 *Example 5.*—The soaping operation is effected as in Example 1. In place of one of the sulphonic acids mentioned, a sulphite waste liquor in a quantity corresponding to its lime-fixing power— $\frac{1}{4}$ to $\frac{1}{3}$ of the quantity required for fixing the lime—is employed. In this case 1.2 to 1.5 ccms. per litre of a preparation containing sulphite waste liquor having a dry content of 12% are necessary.

20 *Example 6.*—The same procedure is followed as in Examples 1-5. Either 0.10 to 0.15 grams of urea or about 0.1 gram of neutral sodium lactate or a corresponding quantity of other stabilizers or peptizing agents 25 is added as well.

In the appended claims we intend the term "aromatic" to include the corresponding hydro-aromatic derivatives as well.

What we claim is:—

30 1. In a process of laundering in hard water the method of rendering harmless the substances contained in said water and which cause hardness thereof, consisting in adding to the water and ordinary soap a derivative of 35 an aromatic sulphonic acid, which forms a water-soluble calcium salt and which has colloidal properties, in a proportion less than the quantity chemically equivalent to said substances contained in the water.

40 2. In a process of laundering in hard water the method of rendering harmless the substances contained in said water and which cause hardness thereof, consisting in adding to the water and ordinary soap a compound 45 comprising an aromatic sulphonic acid radical having an alkyl side chain, said compound forming a water-soluble calcium salt and having colloidal properties, in a proportion less than the quantity chemically equivalent to 50 said substances contained in the water.

3. In a process of laundering in hard water the method of rendering harmless the substances contained in said water and which cause hardness thereof, consisting in adding 55 to the water and ordinary soap a compound comprising a radical obtainable by sulphonating a polynuclear aromatic hydrocarbon containing an alkyl side chain with more than two carbon atoms, said compound forming

60 a water-soluble calcium salt and having colloidal properties, in a proportion less than the quantity chemically equivalent to said substances contained in the water.

4. In a process of laundering in hard water 65 the method of rendering harmless the sub-

stances contained in said water and which cause hardness thereof, consisting in adding to the water and ordinary soap a compound obtainable by sulphonating a polynuclear aromatic hydrocarbon containing an alkyl side chain with more than two carbon atoms, and then treating a fatty oil with the reaction product, said compound forming a water-soluble calcium salt and having colloidal properties, in a proportion less than the quantity chemically equivalent to said substances contained in the water.

5. In a process of laundering in hard water the method of rendering harmless the substances contained in said water and which cause hardness thereof, consisting in adding to the water and ordinary soap a compound obtainable by sulphonating a polynuclear aromatic hydrocarbon containing an alkyl side chain with more than two carbon atoms and then treating castor oil with the reaction product, said compound forming a water-soluble calcium salt and having colloidal properties, in a proportion less than the quantity chemically equivalent to said substances contained in the water.

6. In a process of laundering in hard water the method of rendering harmless the substances contained in said water and which cause hardness thereof, consisting in adding to the water and ordinary soap a compound obtainable by sulphonating a polynuclear aromatic hydrocarbon containing an alkyl side chain with more than two carbon atoms and then treating a fatty oil with the reaction product in the presence of concentrated sulphuric acid, said compound forming a water-soluble calcium salt and having colloidal properties, in a proportion less than the quantity chemically equivalent to said substances contained in the water.

7. In a process of laundering in hard water the method of rendering harmless the substances contained in said water and which cause hardness thereof, consisting in adding to the water and ordinary soap a compound obtainable by sulphonating a polynuclear aromatic hydrocarbon containing an alkyl side chain with more than two carbon atoms and then treating castor oil with the reaction product in the presence of concentrated sulphuric acid, said compound forming a water-soluble calcium salt and having colloidal properties, in a proportion less than the quantity chemically equivalent to said substances contained in the water.

In testimony whereof we affix our signatures.

GUSTAV ULLMANN.
WILLY SECK.
